RUN-UP TRAIN CONTROL

Filed Aug. 17, 1923

FIG. I.

Fig. 2.

FIG. 3.

INVENTOR:

Charles Messick

UNITED STATES PATENT OFFICE

CHARLES MESSICK, OF BRENTWOOD, NEW YORK

RUN-UP TRAIN CONTROL

Application filed August 17, 1923. Serial No. 657,882.

An object of this invention is to provide a simple and sturdy control system and apparatus and specifically one which will avoid interference with train operation and yet provide effective safeguarding of the train in the event of inattention or illness of the engineer or defective visibility of the wayside signals.

Broadly, this run up system is designed to 10 restrict the speed of a train in inverse ratio to the number of track impulses received by the train carried control apparatus.

In the preferred construction the run up device has an arc of movement of 60° and 15 is driven toward its up position continuously by a train carried constant speed motor. The preferred arrangement of the system also includes a combined differential gear and escapement, a differential inductor, and other 20 improved mechanical and electro-magnetic devices and circuits.

As the train advances each track impulse releases the run up device and permits it to fall 30°, the effects of successive partial releases being cumulative. If the train encounters successive track impulses faster than the motor raises the run up device the brakes are applied and the train is brought to a full stop.

25 The track impulses may be applied manually or by wayside automatic block signal apparatus in any conventional manner.

Referring to the accompanying drawings: 30 Fig. 1 is a diagrammatic side elevation of the system and associated apparatus;

Fig. 2 is a plan view of the run up mechanism, which is also partly shown in dotted lines in Fig. 1; and

Fig. 3 is a view of some of the parts shown 40 in dotted lines in Fig. 1.

The numerals 1—1—1—1 indicate sleepers upon which are supported a track rail 3, and also a typical track inductor or inert track element 5, which is provided with a winding 45 7, normally open circuited at the relay 9.

In the normal condition the track inductor 5, forms a magnetic path capable of closing a magnetic circuit in a train carried inductor, which will be subsequently described, but the inductor 5 may be rendered non-inductive 50 by closing the circuit through winding 7 at relay 9.

The relay 9 may be closed by the energization of its winding 11 by the battery 13 when the relay 15 is closed. When this occurs the 55 track inductor 5 becomes non-inductive and incapable of affecting a train carried inductor running over it to any considerable extent.

The relay 15 may be operated by ordinary 60 block signal apparatus, by hand, or in any conventional manner. The number of track elements, like 5, in the inductive condition which a train runs over in a particular block of track, their position in the block, and with 65 respect to each other, limits the train speed by controlling the train carried apparatus, which will be subsequently described.

The position and number of track elements, such as 5, and their control must be determined for each block of track in accordance 70 with the individual traffic and physical conditions found in the block.

The above described apparatus, designated by the numerals 1 to 15, inclusive, is all permanently positioned along the railroad and the apparatus described hereafter, designated by numerals commencing with the numeral 21, is carried by the train, which is a term used to designate any kind of rolling 75 stock.

The train carried differential inductor 21 consists of an H-shaped soft iron magnetic core having a central portion 23, lower pole pieces 25 and 27 between which there is an 80 air gap of, for instance, 24 inches, and upper pole pieces 29 and 31 between which there is an air gap of, for instance, 12 inches.

When the train carried inductor 21 moves 85 in the direction of the arrow 32 and over a 90

track element 5, the magnetic path between pole pieces 25 and 27 is shortened to, for instance, two 3 inch air gaps and passes through the track element 5.

5 However, as previously stated, such a shortening of the magnetic path is avoided if the relay 9 is closed. In this event, the magnetic condition of the train carried inductor 21 remains undisturbed, as if the track 10 element 5 had been physically removed from the roadbed.

From a train carried source of alternating current 41, a wire 43 is connected to a wire 45, a winding 47, a wire 49, a winding 51, a 15 wire 53, through a relay 55, which is closed in the indicated position, a wire 57 to the binding post 58, of a relay 59, from the binding post 58 to a wire 61, a wire 63, and back to source 41.

20 The above circuit energizes the winding 51, but not the winding 47, as the circuit from the winding 47 continues through a wire 64 to relay 59, which is open in the indicated position. When relay 59 is closed, as will be 25 subsequently described, winding 47 becomes energized.

The primary winding 65 of the train carried inductor 21 is continuously energized from the source 41 via wires 43 and 67, winding 65, and wires 61 and 63, back to source 41. In the indicated position of the train four-fifths of the flux induced in the core member 23 jumps the 12 inch air gap, thus powerfully energizing the secondary winding 71.

35 Current from winding 71 flows in through wire 73, winding 75, wire 77, winding 79, wire 81, winding 83, and wire 87 back to source 71. Thus winding 75 closes relay 55, winding 79 opens relay 59, and winding 83 closes relay 85.

One-fifth of the flux induced by the primary winding 65 flows across the 24 inch air gap in the indicated position and induces a weak current in secondary winding 91, which 45 flows via wire 93, winding 95, wire 97, winding 99, wire 101, winding 103, wire 105, and back to source 91, thus relay 107 is closed even though the current is weak. However, relay 55 remains closed and relay 59 remains 50 open as long as the current from source 91 remains only one-fifth as great as the current from source 71.

When the inductor 21 runs over a track element 5 in the inductive condition (but not 55 otherwise) the magnetic path from pole piece 25 to track element 5 and back to pole piece 27 only includes two 3 in. air gaps. Thus the induced current in secondary winding 91 becomes momentarily four times as great as 60 the induced current in secondary winding 71, the magnetic path through which always includes the 12 in. air gap.

At such a moment the windings 95 and 99, which are in circuit with secondary winding 55 91, overcome windings 75 and 79, respectively.

ly, thus opening relay 55 and closing relay 59, respectively. This momentarily opens the circuit through winding 51 and closes the circuit through winding 47 through wires 53 and 64, respectively.

70 Relays 85 and 107 remain closed as long as there is any current, even though small, flowing through their respective windings 83 and 103. These relays may be considered as circuit breakers of the no voltage release type, and they are designed solely to open the direct current circuit which passes through them in series, and to be subsequently described, in the event of a complete failure of current in the circuit from either or both of the secondary windings 71 and 91.

75 The numeral 111 indicates a source of direct current connected via a wire 113 to a constantly running constant speed motor 115 which drives a worm 116. From the motor 115 the circuit is completed back to the source via a wire 117.

80 Wire 113 also connects with a winding 121 which holds closed a relay 123, which is positioned so that the engineman must descend from his cab to the roadside to close same. This circuit continues in the indicated position through the relay 123 and via a wire 124 to the winding 125 which holds closed the air valve 127, except when an automatic brake 95 application occurs.

85 From winding 125 the circuit continues via wire 129 through relay 85, wire 131, relay 107, wire 133, and a conventional push-button snap switch 135 and back to source 111 via 100 wire 117. The switch 135 is made self-opening by means of a compression spring 137, except when the spring is overcome by a superior force, such as is exerted by the lever 139 in the indicated position.

105 Lever 139 is pivotally mounted at its lower end and provided with a roller 141 at its upper end. The roller 141 bears on the larger radius portion 142 of a cam 143 in the indicated position, and when the cam falls 40°, or more, the roller is forced to the right by the spring 137 against the smaller radius portion 145 of the cam 143.

110 This causes the switch 135 to open, breaking the circuit between wires 117 and 133, 115 thus de-energizing winding 125, applying the brakes, and de-energizing winding 121 and opening relay 123.

120 When relay 123 is thus opened the engineman must descend to the roadside and close same before the air valve will again close, even though the switch 135 has been automatically closed, as will be subsequently described.

125 Cam 143 is rigidly secured to an arm 147, which has an enlarged portion 148 pivotally mounted on a suitably mounted horizontal shaft 149. The arm 147 has a radial up and down movement of 60° between stops, 130 as indicated, and its movements are con-

trolled by the bevel gears 150—151, which are journaled on stub-shafts integral with the enlarged portion 148, as indicated, and held in place by collars 152—154, secured to 5 the stub-shafts.

A worm wheel 153 is continuously driven at, for instance, ten revolutions per hour in the direction of the arrow 155 by the worm 116 and motor 115, previously described.

10 Worm wheel 153 is loosely journaled on shaft 149 and provided with a friction plate 157 integral with the worm wheel. Friction plate 157 engages in slipping or driving relation with a friction plate 159, according 15 to the resistance encountered. Plate 159 is provided with a bevel gear 163 integral with the plate, both being rigidly fastened to shaft 149 and gear 163 meshes with gears 150—151.

The frictional engagement between friction plates 157 and 159 is designed to be overcome by worm 116 and permit slippage when the parts are in the indicated position, and to maintain driving relation at all other times in the direction of arrow 155. A spring 165

20 compressed between a collar 167 rigidly mounted on shaft 149 and a ball thrust bearing 169 abutting against the worm wheel 153 compresses plate 157 against plate 159 to effect the above friction driving relation.

25 The bevel gears 150—151 also mesh with a bevel gear 171, which is integral with an escape wheel 173, both being journaled on the shaft 149 and held in place by a collar 174, which is rigidly attached to the shaft 30 149.

The gearing, including gears 163, 150—151, and 171, is essentially a differential gear which exhibits the following characteristics:

35 When gear 163 is turned in the direction of arrow 155 and gear 171 is held stationary by escape wheel 173, gears 150—151, lift arm 147, and the cam 143 which it carries into the indicated up position abutting the stop.

40 Thereafter the clutch plate 157 slips on the clutch plate 159 until the escape wheel 173 is released by the escape lever 175.

The lower portion 177 of the escape lever 175 acts as an armature, which reciprocates between soft iron horse shoe magnet yokes

45 50 179 and 181 when the cam 143 falls by gravity, turning the escape wheel 173 in the direction of the arrow 182, in the event of both yokes being in an inert condition. In the indicated position yoke 181 is magnetized by the winding 51, as previously described,

55 and thus armature 177 is held against yoke 181 and the escape wheel 173 is not permitted to escape.

60 When the train carried inductor 21 runs over a track element 5 and the circuit through winding 51 is momentarily broken, as previously described, armature 177 escapes to the left and strikes against yoke 179, where it

65 is held momentarily by the momentary ener-

gization of the winding 47 of yoke 179, as previously described.

This permits the escape wheel to escape 30° in the direction of arrow 182. When the track element 5 is run past, the winding 47 70 again becomes de-energized and winding 51 energized, thus armature 177 is released from yoke 179 and caught and held at yoke 181 in the indicated position. The escape wheel 173 has thus been permitted to rotate an additional 30° in the direction of arrow 182.

75 Each 30° escape of the escape wheel 173 permits the cam 143 to fall 15°, so that when a track element 5 is run over and run past the cam 143 is permitted to fall a total of 30°.

80 If the motor has not had time to run up the cam 143 sufficiently to permit a fall of 30° without the roller 141 reaching the small radius portion 145 of the cam 143, before the next track impulse is encountered, then when such next impulse is encountered and cam 143 falls the roller 141 moves to the right onto the small radius portion 145, and the switch 135 is thrust open by the spring 137. The opening of switch 135 applies the brakes, as 85 previously described.

90 In the above-described construction the number of revolutions per minute of the worm wheel 153 and clutch disk 157 should be regulated to cooperate to the best advantage with the layout of the track elements on any particular railroad.

95 Suppose, for instance, that 6000 feet per minute is decided upon as the maximum running speed of trains in a particular block. Suppose also for convenience of visualization that clutch disk 157 is driven at a constant speed of one revolution in six minutes, then it will rotate 60° in one minute.

100 Suppose also that there are successive track elements, like 5, and in the inductive condition every 6000 feet along the track, then the escapement wheel 173 will be permitted to rotate 60° every 6000 feet at a track element. As it is run past, clutch 157—159 will just 105 restore the arm 147 to the indicated up position during the following 6000 feet of travel before the next track element is encountered.

110 An additional track impulse during such a 6000 foot unit of travel will prevent the complete restoration of the arm 147 to the indicated position, and cause an automatic brake application unless the engineman has reduced the train speed to less than 6000 feet per minute.

115 Additional track impulses or two close together will limit the permissive train speed to any degree desired at the particular length of track where such track impulses occur.

120 The circuits, and as far as practicable the other apparatus, are designed on the closed circuit principle, so that in the event of a failure it will be on the side of safety.

125 In the event of the motor 115 being of the direct current type and provided with a gov-

ernor, as are electric phonograph motors, a second governor may be supplied in series with the usual governor. Thus over-speed of the motor, which is otherwise a remote possibility, may be guarded against.

5 A clutch may be placed between the motor and the worm instead of the indicated position to make the drive of the differential gear more positive, but this and the other changes are mere details of design which may be incorporated to adapt the system to varying conditions, etc.

10 It is also practicable to substitute equivalents for the motor and clutch above described in the preferred construction; for instance, a three-phase alternating current self-starting synchronous motor, an air motor provided with a governor, or a constant speed spring motor. Either the synchronous motor, the 15 air motor, or the spring motor may be stalled when the run up device is in the indicated up position without harming itself. Thus such motors may only run intermittently and no clutch will be required.

20 The indicated 40° large radius arc 142 of cam 143 may be reduced to, for instance, 31°; and the indicated arc of 60° total movement for arm 147 may be reduced to, for instance, 32°. These smaller arcs will give smaller 25 latitude in the cumulative effects of successive track impulses.

30 Other modifications may also be made, but the essence of my invention is pointed out in the following claims.

35 I claim:

1. The combination of a train carried run up apparatus designed to run up at a predetermined rate, independent of train movements or track elements, and a track element 40 to partly run it down provided with controllable means to prevent the track element acting.

2. The combination of a train carried run up apparatus provided with a unidirectional 45 run up motor, an escapement, means to normally prevent escape and a controllable track element to cause escape when desired.

3. The combination of a train carried apparatus provided with a differential gear and 50 a motor to drive half thereof, a normally immovable escapement to sustain the other half of the gear, and track means to cause escape when required.

4. The combination of a cab carried constant speed run up device provided with 55 means to limit the distance it can run up, an escapement to permit the run up device to fall down and approach a brake applying position or to apply the brakes according to the 60 position which it occupied before escape and a track element to release the escapement when required.

5. A cab carried source of alternating current, a differential inductor energized thereby, a no voltage cut-out normally closed by a

secondary current from the inductor, a train stop normally closed by another secondary current from the inductor, and a track element designed to vary the relative strengths of the two secondary currents at the inductor, when desired, and thus control the train stop.

6. Normally inert track elements, means to render same inductive when the track ahead is not clear, and a cab mechanism including a drop-down device designed to move a predetermined distance when a first track element in inductive condition is run over and to move another predetermined distance when a second track element in inductive condition is run over.

7. The combination of a track provided with a number of inert track elements having normally open circuited windings, means to close circuit one or more of said windings when required for the control of traffic, a train carried half transformer designed to operate a release device at an open circuited track element and a drop down device designed to fall part way when so released and to fall to a lower position at a second track impulse and stop the train.

8. The combination of a control motor of predetermined speed, a run up device actuated thereby, an apparatus to be controlled, means to cause the run up device to be released upon the occasion of a predetermined condition occurring in the apparatus and means to control the apparatus by the release of said run up device.

9. The combination of a control motor of predetermined speed, a run up device actuated thereby, an apparatus to be controlled, means to cause the run up device to be released upon the occasion of a predetermined condition occurring in the apparatus and means to control the apparatus selectively in accordance with the then condition of the run up device.

10. The combination of a constant speed run up normally inactive control device, designed to control an apparatus, provided with means to limit the distance it can run up, an escapement to permit the run up device to fall down and approach an active position according to the position which it occupied before escape and means to release the escapement when required for the control of the apparatus.

11. The combination of an apparatus to be controlled, a control device provided with a differential gear, a motor to run same up, an escapement to normally hold the device inoperative, and means related to the operation of and connected to the apparatus to release the escapement as required to control the apparatus.

12. The combination of a predetermined speed run up normally inactive control device, designed to control an apparatus, an escapement to permit the run up device to fall

down and approach an active position according to the position which it occupied before escape and means to release the escapement when required for the control of the apparatus.

5 13. A control device designed to control an apparatus, provided with a differential gear, means to run same up, an escapement to normally hold the device inoperative, and means related to the operation of and designed to be connected to the apparatus to release the escapement as required to control the apparatus.
